[57] CLAIM

The ornamental design for a steering wheel rim, for
motorcars and watercraft, as shown and described.

DESCRIPTION

FIG. 1 is a front elevational view of a steering wheel
rim for motor cars and watercraft showing my new
design, it being understood that the rear is a mirror
image thereof; and

FIG. 2 is a side elevational view of FIG. 1, the opposite
side being a mirror image thereof.

The broken lines in FIG. 1 of the drawing are for illus-
trative purposes only.
